UNITED STATES PATENT OFFICE.

EDGAR J. BLOOM, OF TIFFIN, OHIO.

FORCE PUMP.

Application filed December 14, 1921. Serial No. 522,214.

To all whom it may concern:

Be it known that I, EDGAR J. BLOOM, a citizen of the United States, residing at Tiffin, in the county of Seneca and State of Ohio, have invented certain new and useful improvements in Force Pumps, of which the following is a specification.

This invention relates to force pumps and has for its object a pump especially designed 10 for chassis lubrication on an automobile and for lubricating other machinery. One of the new types of lubrication being introduced is chassis lubrication from a common and centralized source. By this arrangement it is 15 possible to lubricate the shackle bolts and even some of the points on the running gear, such as the knuckle pins, drag link bolts, etc.

It is the object of the present invention to 20 provide a force pump of improved construction to be mounted on the dash of the car. The specific improvement is an arrangement which permits the charging of the pump chamber ahead of the plunger without requiring the leather cup washers passing 25 an intake orifice. Anyone who has had experience with leather cup washers knows that they are very easily deranged and very often made useless when the cup washer 30 passes an orifice or any irregularity in the passage containing it.

It is the object of the present invention to provide a valve through the plunger which opens up fully on the final portion of the 35 back stroke. This valve closes against its seat tightly on the initial movement of the plunger forward which forces the charge ahead of the plunger. The plunger then forces the charge out of the pump. In short, 40 the force pump has a plunger in which is a valve and passage which serves with the aid of gravity to take in a charge ahead of the main plunger to do away with the necessity of having the cup washers pass the intake 45 orifice. This will more fully appear from the description following.

The operating force may be either a direct pull on the plunger rod or may have the mechanical advantage of a screw.

50 In the drawings,—

Fig. 1 is a cross section through a portion of the dash and foot board showing the lubricating reservoir and force pump in position.

55 Fig. 2 is a longitudinal section showing

the plunger rod fully drawn back and the charging chamber opened.

Fig. 3 is a similar view showing the plunger in an intermediate position and the valve closed. In this view the stroke of the 60 plunger is effected by a screwing action.

Fig. 4 is a section on the line 4—4 of Fig. 2.

Fig. 5 is a section on the line 5—5 of Fig. 2.

a designates the dash of the car; *z* the foot board. It is preferable to secure the oil reservoir and pump to the dash, but, of course, it is immaterial where it is placed. I have provided a special form of fixture 70 which comprises a threaded socket member *b* which may be secured to the hood side of the dash by screws *c*. By loosening the lock nut *d* the threaded eye bolt *e* may be turned one or more half-turns in or out of the 75 socket to adjust its position correctly with the force pump *f* so that this eye bolt will be properly arranged to encompass the neck of the ball-like oil reservoir *g*. This oil reservoir is provided with a nipple *h* that 80 screws into a tapped opening *i* in the barrel of the force pump.

This barrel of the force pump does not act as the cylinder of the pump; it acts simply as an oil reservoir *j*. The pump cylinder *k* screws into the end of the barrel *f* and in this reciprocates an ordinary form of pump plunger which is provided with either one or two leather cup washers *m*. These washers work very well in a pump provided they 90 do not have to pass any irregularity or orifice which is likely to stroke them the wrong way on movement of the plunger in one direction. It is the object of the present invention to so arrange the intake of the oil 95 that it is unnecessary for these leather cup washers to pass an irregularity or an orifice.

The plunger itself has at its rear a cylinder *n* or valve guide which forms a continuation of the plunger that carries the cup washers. The rod *o* instead of being connected to the plunger has a positive connection only with the valve *p* which is attached to its end. A nut *q* screws into the end of 100 the cylinder or valve guide *n* and between this and the plunger is a coiled spring *r* which embraces the bushing *s*. This spring holds the valve *p* to its seat *u* and prevents 105 any leakage from the reservoir in case of 110

breakage in the feed pipe lines. The sides of the cylinder *n* are recessed to provide ports *t* which afford a large port area for the quick filling with the aid of gravity of the working chamber ahead of the plunger. At the end of the chamber is a packing washer or valve seat *u*.

Screwing into the face of the barrel *f* is a supplemental barrel *v* which performs two important functions. One is that the end of this barrel forms a stop to engage the nut *q* and thereby stop the inward movement of the main portion of the plunger so as to permit the rod *o* to draw the valve *p* away from its seat and thereby open up the passage through the plunger. The other function of the supplemental barrel is to afford a cylinder in which reciprocates another cup washer *w* on a small plunger attached to the rear of the rod so as to provide a secondary seal so as to prevent any of the lubricant finding its way back out of the face of the fixture. The main cylinder *k* is purposely made slightly larger than the barrel *v* so that when the turn handle *x* and lock nut *z* is taken off the rod, the main plunger and the valve may be disassembled by drawing them through the cylinder *k*, after the coupling nut *y* has been taken off. The cylinder *k* being larger than the supplemental barrel *v*, the cup washer *w* can readily pass through it.

The operation has probably already been understood. When the oil flows easily and no great force is required the nut *z* can be run off the threads at the end of the supplemental barrel *v*, as is shown in Fig. 2. The plunger rod is drawn back and the nut *q* or the rear end of the plunger strikes the end of the supplemental barrel *v*. Further backward movement of the rod thereby causes the valve *p* to separate from its seat *u*, thereby opening the passage through the plunger. The lubricant through gravity immediately fills the working chamber ahead of the plunger due to the large orifice on both sides which open directly into the reservoir *j* of the main barrel *f*. The bushing *s* prevents the valve moving backward except a given distance and hence limits the valve opening.

The movement of the rod is then reversed and the valve *p* being held to its seat *u* by the operating force and the spring *r* keeps the fluid from forcing back and the plunger forces the fluid ahead of it on the working stroke. If there is any leakage whatever here the supplemental cup washer *w* prevents the same from escaping from the pump along the handle of the pump.

From this description it will be seen that the leather cup washers *m* are confined strictly in the smooth uninterrupted bore of the cylinder *k* and are in no way affected by any irregularity such as a port opening.

The cup washer *w* keeps any of the oil which fills the chamber of the barrel *v* from leaking out the rear of the barrel due to the action of gravity. Additionally if there is any leakage around the valve *p* and its seat, causing back pressure, this cup washer *w* prevents the oil forcing out around the operating rod.

What I claim is:

1. In a force pump, the combination of a cylinder, a plunger provided with a passage longitudinally therethrough and a rearwardly extending supplemental cylinder, and a valve guided in the supplemental cylinder for controlling such passage to allow the charging of the chamber ahead of such plunger.

2. A force pump, having in combination, a cylinder, a plunger provided with a passage therethrough and reciprocating in the cylinder, a supplemental cylinder secured to the rear of the main plunger and having one or more ports at the sides, and a valve reciprocating in such supplemental cylinder and arranged to open and close the passage through the plunger.

3. A force pump, having in combination, a main cylinder, a plunger provided with a passage therethrough and reciprocating in the cylinder, a supplemental cylinder secured to the rear of the main plunger and having one or more ports at its side, a valve reciprocating in the supplemental cylinder and controlling the said passage through the plunger, a rod connected with the valve, a spring normally spacing the valve from the rear end of the cylinder and arranged to keep it closed, and a stop member which arrests the plunger before the stroke backward is entirely completed and permits a continuation of the pull on the rod to compress the spring behind the valve and thereby allow the valve to open.

4. A force pump, having in combination, a main cylinder, a plunger provided with a passage therethrough and reciprocating in the main cylinder, a supplemental cylinder secured to the rear of the plunger, a valve reciprocating in said supplemental cylinder, a rod secured to such valve, a barrel, a plunger on the rear end of the rod provided with a suitable packing member reciprocating in said barrel, and a stop for arresting the main plunger in its backward movement to permit the rod to draw the valve back independently of the plunger to open the passage through the plunger.

5. A force pump, having in combination, a main cylinder, a plunger reciprocating in the same and provided with a passage therethrough, a supplemental cylinder supported at the rear of the plunger, a valve guided therein and controlling said passage, a rod secured to the valve, a barrel encompassing the rod and whose end is

adapted to strike the end of the supplemental cylinder to arrest the plunger on the backward stroke to permit the valve to open ahead of the supplemental plunger, 5 and a second plunger secured to the rear of the rod and provided with suitable packing means reciprocating within the said barrel.

6. A force pump, having in combination, a barrel containing a fluid reservoir space, 10 a main cylinder secured to the barrel, a plunger reciprocating in said cylinder and provided with a passage therethrough, a supplemental cylinder at the rear of the main plunger provided with one or more 15 ports opening into the reservoir space of the barrel, a valve reciprocating in the said supplemental cylinder and controlling said passage, a rod by which the plunger and valve are operated secured to the valve, the said 20 plunger being arrested in its backward movement to permit the valve to draw back from its seat, said valve movement inward closing against its seat and the plunger forcing the fluid ahead.

25 7. In a force pump, the combination of a barrel provided with a reservoir space, a main cylinder secured to the front end of the barrel, a plunger provided with a passage therethrough and reciprocating in such 30 cylinder, a supplementary cylinder secured to the rear end of the plunger and provided with one or more ports communicating with the oil reservoir portion of the barrel, a valve reciprocating in such supplemental 35 cylinder and controlling said passage, a supplemental barrel secured in the rear end of the main barrel and having one end operating as a stop for the plunger, and a rod secured to the valve, whereby when the rod 40 is drawn backward and the plunger is arrested by the end of the supplemental barrel the valve is drawn back off its seat, the said valve being closed upon the initial forward movement of the rod and the plunger forces 45 the fluid ahead of the same.

8. In a force pump, a barrel provided

with a liquid reservoir, a cylinder secured to the front end of said barrel, a plunger reciprocating in said cylinder and provided with a passage therethrough, a cylinder 50 provided with ports communicating with said reservoir and secured to the rear end of the main plunger and provided with a packing washer at the front end, a valve reciprocating in such supplemental cylinder 55 and arranged to close against said washer, a rod secured to such valve, a supplemental barrel secured to the rear end of the main barrel and having its front end in the path of the supplemental cylinder to arrest the 60 plunger and permit the rod to draw back the valve from its seat, whereby upon the initial movement of the rod inward the valve seats against the packing member at the forward end of the supplemental cylinder 65 and continued movement of the plunger forces the lubricant ahead of the plunger.

9. In a force pump, the combination of a barrel provided with a liquid reservoir, a main cylinder secured to the forward end of 70 the barrel, a plunger reciprocating therein and provided with a passage therethrough, a supplemental cylinder secured to the rear end of the main plunger and provided with one or more ports communicating with the 75 liquid reservoir portion of the barrel, a valve reciprocating in the supplemental cylinder and controlling such passage, a plunger rod secured to such valve, a supplemental barrel secured to the rear end of the main barrel 80 and projecting into the path of the supplemental cylinder to arrest the rearward movement of the plunger, a second plunger secured to the rear end of the rod and having packing means engaging the supplemental barrel, and a packing washer at the forward end of the bore of the supplemental cylinder against which the valve engages 85 after the initial movement forward.

In testimony whereof I affix my signature.

EDGAR J. BLOOM.
